UNITED STATES PATENT OFFICE.

FRANK E. THOMPSON AND CHARLES LEDIN, OF STAMFORD, CONNECTICUT, ASSIGNEES
TO THE YALE & TOWNE MANUFACTURING COMPANY, OF STAMFORD, CONNECTICUT.

FACING-RING STRUCTURE FOR CYLINDER LOCKS.

Application filed October 30, 1922. Serial No. 597,916.

To all whom it may concern:

Be it known that we, FRANK E. THOMPSON and CHARLES LEDIN, citizens of the United States, and residents of Stamford, 5 in the county of Fairfield and State of Connecticut, have invented certain new and useful Improvements in Facing-Ring Structures for Cylinder Locks; and we do hereby declare the following to be a full, clear, 10 and exact description of the invention, such as will enable others skilled in the art to which it appertains to make and use the same.

This invention relates to improvements 15 in facing or rose ring structures for cylinder locks,—one object of the invention being to provide a structure of this character which shall embody a substantial armor structure and also provide yielding 20 means whereby the head portion of a cylinder lock shall have a proper close fit relatively to the facing ring when it is necessary to turn the cylinder in such manner as to insure the location of the plug 25 of the lock in the lower portion of the cylinder when the lock is applied to a door.

With this and other objects in view, the invention consists in certain novel features as hereinafter set forth and pointed out in 30 the claims.

In the accompanying drawings,—

Figure 1 is a sectional view of a facing ring structure embodying our improvements 35 and showing the application of the same to a cylinder lock, the latter being represented in elevation, and

Figures 2 and 3 are front and sectional views illustrating a modification.

In the embodiment of our invention 40 shown in Figure 1, the body portion of a facing ring 1 made preferably of steel or hardened metal is employed and this ring is provided interiorly with an annular recess 2 forming a shoulder 3 at its base. A 45 tapering annular spring 4, preferably of flat spring metal is located in the recessed ring 1 and one end of the spring is seated against the shoulder 3 which forms the bottom of the annular recess 2 while the outer end of 50 said spring bears against a ring 5 located within the recess 2. Outward displacement of the ring 5 may be prevented by engagement with an inwardly projecting portion 6 of a scalp 7 with which the body of 55 the facing ring is provided.

The ring 5 constitutes an abutment for the flanged or headed end 8 of the lock cylinder 9 and the spring 4 will constitute yielding means which will permit a proper close fit of the headed end of the cylinder 60 relatively to the facing ring, while the hardened metal of the ring 1 will serve as an armor to resist penetration of a boring tool and thus protect vital parts within the lock cylinder. 65

In the embodiment of our invention shown in Figures 2 and 3, a corrugated spring member 10 is employed and this spring member is split and forms somewhat less than a complete circle as clearly shown 70 in Figure 2. In other respects the construction shown in Figures 2 and 3 may be the same as shown in Figure 1.

Having fully described our invention what we claim as new and desire to secure 75 by Letters-Patent, is:

1. The combination of a facing ring having a solid body portion of hardened metal, a spring member carried by the body portion to yieldingly press against the flanged 80 head of a lock cylinder, and a metal scalp covering the said body portion of the facing ring.

2. The combination of a facing ring having a solid body portion of hardened steel, 85 a spring member carried by said body portion to yieldingly press against the flanged head of a lock cylinder, and a metal scalp covering the said body portion of the ring and constituting limiting means for the 90 spring member.

3. In a facing ring structure, the combination of a facing ring having an interior recess forming an annular seat, a spring located within the recessed ring and bearing 95 against said annular seat, and a ring also bearing against said spring and adapted to receive the flanged end or head of a lock cylinder.

4. In a facing ring structure, the combination of a facing ring having an internal recess forming an annular seat, a coiled spring located within said recessed ring and having one end bearing against said seat, and a ring 100 engaging the other end of said spring and adapted to receive the flanged or headed end of a lock cylinder. 105

5. In a facing ring structure, the combination of a facing ring having an internal recess forming an annular seat, a coiled spring 110

bearing at one end against said seat, a ring against which the other end of said spring bears, and a scalp on the facing ring and having an inwardly projecting part constituting an abutment for the ring at the outer end of said spring.

6. In a facing ring structure, the combination of a facing ring, and a tapering coiled spring disposed in said facing ring and 10 adapted to surround a lock casing passing

through said ring and to be co-operable with the head portion of the lock casing.

In testimony whereof, we have signed this specification in the presence of two subscribing witnesses.

FRANK E. THOMPSON.
CHARLES LEDIN.
